UNITED STATES PATENT OFFICE.

MICHAEL F. WEIDENBACH AND FRANK B. PETERS, OF MINNEAPOLIS, MINNESOTA, ASSIGNORS TO MANUEL-SMITH HEATING COMPANY, OF MINNEAPOLIS, MINNESOTA, A CORPORATION OF MINNESOTA.

COMBINED HEATING AND VENTILATING SYSTEM.

No. 921,033.

Specification of Letters Patent. Patented May 11, 1909.

Original application filed September 18, 1907, Serial No. 393,525. Divided and this application filed December 23, 1907. Serial No. 407,872.

To all whom it may concern:

Be it known that we, MICHAEL F. WEIDENBACH and FRANK B. PETERS, citizens of the United States, residing at Minneapolis, in the 5 county of Hennepin and State of Minnesota, have invented certain new and useful Improvements in Combined Heating and Ventilating Systems; and we do hereby declare the following to be a full, clear, and exact description of the invention, such as will enable others skilled in the art to which it appertains to make and use the same.

This invention relates to combined heating and ventilating systems and is particularly 15 directed to improved means for drawing in fresh air, heating the same and discharging the same into a room.

The present application is filed as a division of our co-pending application S. N. 26 393,525, filed September 18, 1907, entitled combined heating and ventilating systems.

The invention consists of the novel devices and combinations of devices hereinafter described and defined in the claims.

25 In the accompanying drawings which illustrate the invention, like characters indicate like parts throughout the several views.

Referring to the drawings, Figure 1 is view 30 in side elevation, with some parts broken away and some parts in vertical section, illustrating the invention applied in connection with an air jacketed stove, such as usually employed in school houses and stores; and Fig. 2 is a plan view of the parts shown 35 in Fig. 1.

The stove or heater 1, which may be of any suitable design, is inclosed within a surrounding jacket 2 that is open at its top and bottom and is spaced apart from said stove, so 40 as to leave an annular air chamber between the same and the stove.

The numeral 3 indicates the smoke pipe which, as shown, leads upward from the top of the stove and may be of the usual or any 45 suitable construction and arrangement.

As the novel feature of this invention, an air heating chamber 4 is applied directly to the outside surface of the stove 1 in such manner that the embraced side portion of the 50 stove constitutes one side of the said air heating chamber. At its top this air heating chamber 4 is open and at its bottom it is

closed except for a cold air intake pipe 5 which leads downwardly and laterally therefrom and through one of the walls 6 of the 55 building to the outside of the building. The fresh air from the outside of the building will be drawn into the room through the intake pipe 5 and will be heated in the compartment 4; and, after it is heated and has attained a 60 rapid upward movement, will be commingled with the hot air which is passing upward through the annular space formed between the stove and the surrounding jacket 2. The cold fresh air drawn in through the pipe 5 is 65 thus directly brought into contact with the exterior of the stove where it will be very quickly heated. It will also be understood that it is important that the fresh air be heated and given its direct upward movement before it is commingled with the other 70 hot air circulated through the jacket 2 as above described.

The cold air intake and heating device above described while capable of general use 75 is especially adapted for use in connection with a ventilating system such as that disclosed and claimed in our co-pending application above identified, and wherein the cold foul air is drawn out of the room from a point 80 near the floor.

The term "stove" is herein used in a broad sense to include a furnace or any kind of fuel burning heater.

What we claim is:

1. The combination with a stove and a surrounding jacket that is open at both top and bottom, of a heating chamber applied directly to one side of said stove with the embraced portion of the stove constituting 90 one side of said heating chamber, the said chamber having an open top, and a fresh air intake pipe opening into the bottom of said heating chamber, whereby the cold fresh air will first be heated by direct radiation from 95 the stove and will then be commingled with the upwardly moving hot air in the space between said stove and surrounding jacket, substantially as described.

2. The combination with a stove and a 100 surrounding jacket that is open at both top and bottom, of a heating chamber directly applied to one side of said stove with the embraced portion of the stove constituting one

side of said heating chamber and with the opposite side of said heating chamber spaced apart from said jacket so as to leave an unobstructed air space between the jacket and 5 heating chamber, the said chamber having an open top, and a fresh air intake pipe opening into the bottom of said heating chamber, whereby the cold fresh air will first be heated by direct radiation from the stove and will 10 then be commingled with the upwardly mov-

ing hot air in the space between said stove and surrounding jacket.

In testimony whereof we affix our signatures in presence of two witnesses.

MICHAEL F. WEIDENBACH.
FRANK B. PETERS.
